(57) **CLAIM**

The ornamental design for an automobile wing, as shown and described.

DESCRIPTION

FIG. 1 is a perspective view of an automobile wing, showing my new design;

FIG. 2 is a reduced rear view thereof, showing the automobile wing in its position of use;

FIG. 3 is a reduced top plan view thereof;

FIG. 4 is a reduced front view thereof;

FIG. 5 is a reduced rear view thereof;

FIG. 6 is a reduced side view thereof;

FIG. 7 is an enlarged cross sectional view thereof taken along line 7—7 in FIG. 3; and,

FIG. 8 is an enlarged cross sectional view thereof taken along line 8—8 in FIG. 3.

The broken line showing of environment is for illustrative purposes only and forms no part of the claimed design.
